Patented Dec. 26, 1916.

INVENTOR.

Thomas Lund
By his Attorney
Nelson M. Leonard

UNITED STATES PATENT OFFICE.

THOMAS LUND, OF BEVERLY, MASSACHUSETTS, ASSIGNOR TO UNITED SHOE MACHINERY COMPANY, OF PATERSON, NEW JERSEY, A CORPORATION OF NEW JERSEY.

SPLITTING-MACHINE.

1,209,737.

Specification of Letters Patent.

Patented Dec. 26, 1916.

Application filed December 28, 1915. Serial No. 69,000.

To all whom it may concern:

Be it known that I, THOMAS LUND, a citizen of the United States, residing at Beverly, in the county of Essex and State of Massachusetts, have invented certain Improvements in Splitting-Machines, of which the following description, in connection with the accompanying drawings, is a specification, like reference characters on the drawings indicating like parts in the several figures.

This invention relates to machines for splitting stock and is herein illustrated in connection with a machine for splitting or evening heel lifts.

The type of leather splitting machine which is commonly used comprises a pair of feed rolls located one above the other and a knife located in the rear of said rolls. 20 The knife has a double bevel, its edge being located as near as practicable to the bite of the rolls; and when a piece of stock such as a heel lift blank is fed through the machine the finished lift passes over the knife and 25 the chip or skiving beneath it. The rolls grip the blank along a narrow area with considerable force; and one effect of gripping and splitting the blank in the manner indicated is to impart to the finished lift an 30 objectionable bend or curl.

The general object of the present invention is to take out this curl and to produce a product which shall be flat.

One feature of the invention comprises in 35 a machine of the class described, a pair of rolls for feeding a piece of stock, a knife for splitting a piece so fed, and means located in the rear of said rolls for straightening said piece. This and other features of the 40 invention including certain details of construction and combinations of parts will be described in connection with an illustrative machine and pointed out in the appended claims.

45 Referring now to the accompanying drawing,—The figure is a side elevation of a machine in which the present invention is embodied, certain parts having been broken away and others having been shown in section.

The machine in its general organization is similar to that shown in United States patent to Nash No. 894,850. The feed rolls 1 and 3 are driven in opposite directions 50 through suitable gearing from a driving

shaft 5 so as to feed the stock to a stationary knife 7 which is located in the rear of said rolls. The lower roll is mounted in adjustable bearings which are normally held up against stops by heavy springs 9. The 60 upper roll is mounted in adjustable bearings one of which is shown at 11, the extent of upward movement permitted said bearings being limited by wedges which may themselves be adjusted by turning the hand wheel 13. The thickness of the finished product is determined by the distance from the lowest portion of the upper roll to a horizontal plane through the edge of the knife; and this distance may be varied by 65 manipulating the wheel 13.

The construction which has been outlined above is old and well known, and no further detailed description of it will be given.

With the construction described considerable difficulty has been experienced in that the finished product, particularly when short pieces such as heel lifts are being evened, is more or less permanently bent or curled. 75 By referring to the drawing it will be seen 80 that the chip or skiving 16 is curled downwardly. If no means were provided for exerting pressure upon the finished piece 18, said piece would curl upwardly in a similar manner and this curled or bent condition would be more or less permanent. 85 In order to produce a finished product which shall be flat, a presser 15 is provided which in the illustrative machine has a flat face arranged parallel to the adjacent beveled face of the knife 7 and the knife-clamp 20. As the skived piece of stock begins to bend or curl upwardly it encounters this presser and is pressed down and forced to travel in the straight passageway formed 90 between the presser on one side and the knife and clamp on the other, the tendency to curl upwardly being resisted at all times by the presser. This presser 15 is adjustable with the bearings of the upper roll, 100 being herein shown as fastened to said bearings by screws 17; and the distance from the presser to the adjacent faces of the knife and knife-clamp is made approximately equal to the distance from the lower portion of 105 the upper roll to a horizontal plane through the edge of the knife. The piece of stock is therefore engaged on both sides while being straightened.

Although the invention has been set forth 110

2
in connection with a particular machine, it should be understood that the invention is not limited in the scope of its application to the particular machine shown and described.

Having thus described my invention, I claim as new and desire to secure by Letters Patent of the United States:

1. A machine of the class described having, in combination, a pair of rolls for feeding a piece of stock, a splitting knife located in the rear of said rolls and having its edge close to the bite of the rolls whereby as the piece is split a bend or curl is imparted to it, and means located in the rear of said rolls for removing said curl or bend and thereby straightening said piece.
2. A machine of the class described having, in combination, a pair of rolls for feeding a piece of stock, a splitting knife located in the rear of said rolls and having its edge close to the bite of the rolls whereby as the piece is split a bend or curl is imparted to it, and a member arranged in the rear of said rolls in position to exert pressure upon said piece in a direction and with sufficient force to straighten it.
3. A machine of the class described hav-

ing, in combination, a pair of rolls for feeding a piece of stock, a splitting knife located in the rear of said rolls and having its edge close to the bite of the rolls whereby as the piece is split a bend or curl is imparted to it, and means located in the rear of said rolls and arranged to engage both sides of said piece to straighten it.

4. A machine of the class described having, in combination, a splitting knife for splitting a piece of stock, a pair of rolls for feeding said stock to said knife, adjustable bearings for one of said rolls, and a presser located in the rear of said rolls, the operative face of said presser being substantially parallel to the adjacent surface of the knife.

5. A machine of the class described, having, in combination, a pair of rolls for feeding a piece of stock, a splitting knife located in the rear of said rolls and having its edge close to the bite of the rolls whereby as the piece is split a bend or curl is imparted to it, and means for holding the piece flat during the splitting operation.

In testimony whereof I have signed my name to this specification.

THOMAS LUND.
